UNITED STATES PATENT OFFICE.

FREDERICK J. TAHL, OF CHICAGO, ILLINOIS.

BUTTON-SHANK.

1,056,070.

Specification of Letters Patent. Patented Mar. 18, 1913.

Application filed February 23, 1912. Serial No. 679,410.

To all whom it may concern:

Be it known that I, FREDERICK J. TAHL, a citizen of the United States, residing at Chicago, county of Cook, State of Illinois, have 5 invented a certain new and useful Improvement in Button-Shanks, and declare the following to be a full, clear, and exact description of the same, such as will enable others skilled in the art to which it pertains to 10 make and use the same, reference being had to the accompanying drawings, which form a part of this specification.

My invention has for its object to produce a simple and novel shank for buttons which 15 will permit the buttons to lie close to the garment and which will permit cloth coverings to be easily secured in place by sewing them to the shanks where the shanks are applied to button forms or molds.

20 A further object of my invention is to produce a simple and novel detachable button shank which may be applied to any button mold.

25 The various features of novelty whereby my invention is characterized will herein-after be pointed out with particularity in the claims; but, for a full understanding of my invention and of its object and advantages, reference may be had to the following detailed description taken in connection with the accompanying drawing, wherein:

30 Figure 1 is a perspective view of a shank made in accordance with a preferred form of my invention; Fig. 2 is a section through a button mold to which my shank is applied; and Fig. 3 is a cross section through the head portion of the shank.

35 Referring to the drawing, 1 represents a fabric stem made of a suitable material to permit it to be sewed to a garment and strong enough to resist the strains upon a button which may be carried thereby. On one end of the stem is secured a flanged head, represented in the drawing as consisting of a small sheet metal sleeve 2 having a flange 3 on one end. The head is secured in place by being slipped over the end of the stem and being compressed or otherwise contracted so as to clamp the end of the 45 stem firmly. In the arrangement shown, 50

the sleeve portion of the head is split so as to make the opening therethrough large enough to receive the end of the stem freely. The sleeve is then closed and, if desired, indented at one or more points as indicated 55 at 4 to prevent relative movements between the head and the stem in the direction of the length of the stem. The stem itself may be variously formed, the simplest construction being that in which it is made of a short piece of cord doubled upon itself in 60 the middle and having its ends clamped within the head. This arrangement gives a neat finish to that portion of the shank projecting from the head and also makes 65 the shank strong and durable.

In using the shank a central hole, large enough to receive the body of the shank, is formed through the center of a button mold 5 and the shank is inserted through this 70 hole and pressed down until the flange rests upon the upper surface of the mold and the fabric end projects beyond the back of the mold. The mold may then be covered in any suitable way; if the covering be of fabric it can be stretched over the top of the mold and across the back as indicated by the dotted line 6, being secured at the back by sewing it to the fabric shank. The shank 75 therefore affords a means for fastening the 80 covering on the back side of the mold and also for holding the complete button to the garment. It will also be seen that the flexible shank is soft and yieldable as compared with the usual metal eyelet, permitting the 85 button to lie close to the garment without making a rigid projection which will press against the body of the wearer.

While I have illustrated and described in detail only a single preferred form of my 90 invention I do not desire to be limited to the particular structural details thus illustrated and described, but intend to cover all forms and arrangements which fall within the 95 terms employed in the definitions of my invention constituting the appended claims.

I claim:

1. As an article of manufacture, a button shank comprising a fabric stem and a thin sheet metal sleeve clamped about one end 100

thereof and having a narrow flange at its outer end.

2. As an article of manufacture, a button shank comprising a stem consisting of a piece of cord doubled upon itself, a sleeve of sheet metal clamped about the ends of the cord, and a narrow flange about the outer end of the sleeve.

In testimony whereof, I sign this specification in the presence of two witnesses.

FREDERICK J. TAIHL.
